UNITED STATES PATENT OFFICE.

WILLIAM M. THOMAS, OF LOS ANGELES, CALIFORNIA, ASSIGNOR OF ONE-HALF TO
WILLIAM S. POST, OF LOS ANGELES, CALIFORNIA.

COMBINATION CEILING AND FLOOR CONSTRUCTION.

1,280,586.

Specification of Letters Patent.

Patented Oct. 1, 1918.

Application filed May 25, 1910, Serial No. 563,406. Renewed January 3, 1918. Serial No. 210,230.

To all whom it may concern:

Be it known that I, WILLIAM M. THOMAS, a citizen of the United States, residing at Los Angeles, in the county of Los Angeles and State of California, have invented a new and useful Combination Ceiling and Floor Construction, of which the following is a specification.

This invention relates to a ceiling and floor construction for concrete buildings, and the main object of the invention is to eliminate, as far as possible, the centering which is found necessary in construction of reinforced concrete floor systems. At present floors are built with wooden boxes or troughs brought up to their proper positions and supported by false work consisting of posts, studs or columns, this false work being one of the main expenses encountered in the construction of any reinforced concrete work. The present invention provides for the construction of the floor and ceiling members in convenient location other than that which is to be occupied by them when in permanent position.

Another object of the invention is to provide an improved ceiling and floor construction in which the ceiling serves to take part of the strain on the floor members, said ceiling being formed of slabs provided with seats and the floor is provided with arch beams or their equivalent resting on said seats.

Another object of the invention is to provide a sectional floor construction giving a three-hinge arch which serves the purpose of a solid arch when the structure is finished, and which is convenient and economical in construction.

Other objects of the invention will appear hereinafter.

In accordance with the present invention, floor slabs and arch beams will be made at suitable platforms or molding yards located as near as possible to the building to be erected, and will be transported to the building by suitable means. They are then set on a frame work which may be either the steel structure of a steel frame building, or a temporary structure for a reinforced concrete building. The complete panel of the arch beam slabs is set on top of the ceiling slabs, the arch beams resting on skewbacks provided for them on the ceiling slabs, said arch beam forming a mold for concreting

the beams or girders. The concrete is filled into such mold and after completion of the concrete the arch beams form an elastic arch or dome, and the false work, if any, may be removed.

The accompanying drawings illustrate the invention, and referring thereto:—

Fig. 1 is a transverse section of a portion of the floor and ceiling showing an elastic arch construction for the floor beams.

Fig. 2 is a similar view showing a three-hinge construction for the floor slabs.

Fig. 3 is a transverse section showing the application of the invention in connection with a steel frame structure, the floor member being formed as an elastic arch.

Fig. 4 is a view similar to Fig. 3 showing the application of the three-hinge arch to the steel frame structure.

Fig. 5 is a view similar to Fig. 1 showing a modified form of the ceiling slab giving a single joint on each side of each panel.

Fig. 6 is a section transverse to Fig. 1 showing the panels made in a plurality of sections.

Fig. 7 is a transverse section of a form of the invention provided with means for masking the joint between the ceiling slabs.

Fig. 8 is a perspective showing the manner of building up the structure in a steel frame construction.

Fig. 9 is a detailed perspective showing means for tying the ceiling slabs to the steel frame.

Fig. 10 is a perspective of the tie means.

Fig. 11 is a perspective of a portion of the floor construction and the false work therefor showing the manner in which the ceiling slabs and floor arches are supported temporarily in position to serve as mold means for the reception of the cement to form the girders or beams.

Fig. 12 is a sectional view showing the manner of reinforcing the ceiling slabs and tying the same to the beams.

Referring to Fig. 1, the ceiling slab indicated at 1 is provided with a longitudinal metal reinforcing 2 projecting as at 3 to extend into the beams or girders between the slabs and said ceiling slab is provided at each end with an up-turned hinged seat 4 having upwardly and outwardly inclined faces 4' to serve as a support for the correspondingly inclined ends of the arch beam 5. The end portions of said arch beam are inclined out-

wardly and downwardly to rest on said seat and to form between adjacent arch beams an upwardly flaring space for formation of the T beam or girder. Each of the 5 arch beams 5 is provided with a flat topped central portion and with reinforcing means 6 extending therethrough, said reinforcing means projecting as shown at 7 for interlocking with the T beam or girder 8. The 10 arch beams 5' at each end of each panel may be coved as shown to rest laterally on the side seats 14' as shown in Fig. 6.

In place of the arch beam 5, arch sections 13 may be provided as shown in Fig. 2, said 15 sections forming, when placed together, a three-hinge arch structure similar in shape to the arch beam 5 above described and having, in addition to the reinforcing means 6 auxiliary reinforcing means 16 consisting 20 of wires extending from the upper portion of each arch section 15 obliquely downward and outward into the space to be occupied by the girder or beam 8. Fig. 3 shows a construction suitable for use in connection 25 with steel framing and reinforced concrete flooring and ceiling, the metal I-beams 13 serving to support the ceiling slabs 11 directly, said slabs having shoulders or rabbits 19 resting on the lower flanges of said 30 I-beams and being formed with seats 14 to receive the arch beams 25 which are shown as provided with auxiliary reinforcing means 26 extending obliquely in the lower portion thereof in addition to the reinforcing 35 means 6 in the upper portions of said arch beams. In such application of the invention tie means are provided for holding the ceiling slabs 11 in position on the I-beams, said tie means consisting of rods 21 40 formed with hooks 22 (see Fig. 10), adapted to engage the further flange of the I-beam, said tie rod extending under the I-beam and through an enlarged end portion 23 of the ceiling slab and being provided 45 with a bearing plate 29 and nut 30, said nut screwing on said tie rod to draw the parts tightly into position.

In this form of the invention the ceiling slabs resting directly on the lower flanges 50 of the I-beams leave a space directly beneath said flanges which may be filled with cement, as shown at 20, in a continuous surface, and also interlocking with the tie rods 21. A similar construction may be provided 55 by the use of three-hinge arch sections shown at 35 in Fig. 4, said sections resting at their outer ends against the seats 14 and against the concrete girder means 33 surrounding the I-beams 13 and abutting one 60 another at their inner ends. In the form of the invention shown in Fig. 5 the ceiling slabs 31 abut at their ends to form a continuous ceiling, seats 34 being provided a short distance from each end, said seats 65 having inclined faces 84' serving as seats

for the elastic arch 37 which is of similar construction to that shown in Fig. 1. Reinforcing means 32 extends longitudinally through the ceiling slab 31 and up through the back of the seat 34 into the girder 8. In 70 the form of the invention shown in Fig. 7 the ceiling panel is formed similarly to slab 11 of Fig. 3, and arch slab 15 is similar to that of Fig. 2, the two being assembled and supported on the I-beams of a steel frame 75 structure as in Fig. 3.

In all the above described forms of the invention the cement or concrete is run into the space between the ends of the floor slabs to form the girders or concrete beams, or in 80 a case where steel framing is used, form the concrete fireproofing for the beams, and said concrete is extended over the top of the floor arches or beams to form the permanent floor surface indicated at 18 in each of the figures. 85

The structure is built up as follows, in case, for example of a steel frame building with reinforced concrete floor and ceiling, no false work is required in this case, the ceiling slabs 1 being placed with their end 90 portions resting directly on the lower flanges of the I-beams 13, as shown in Fig. 8, and the arch sections 15 are placed in position with their end portions resting on the seats 14 of said ceiling slabs. Reinforcing rods or members 2 and 6 of the slabs 1 and arch members 15 extend into the space alongside of the I-beams 13 so that when the concrete is poured into the said space the said members 1 and 15 will be interlocked 95 with the concrete beams surrounding the I-beams. 100

In case it is found necessary to take up any tension developed by the thrust of the arch beams the tie means 21 above described are 105 used, tying each ceiling slab 11 to the I-beam at each side. When the parts have thus been assembled as shown in Fig. 8, cement or concrete is run into the spaces between the floor slabs and embeds the I-beams 13, forming 110 armor or fire-proofing for said I-beams and being extended over the arch sections 15 to form the floor 18.

In the construction of a reinforced concrete building false work will be provided 115 comprising, for example, posts 38 and temporary girders or beams 39, said girders extending directly under the position of the permanent girders and being slightly wider than the permanent girders which are to 120 be formed of reinforced concrete. The ceiling slabs 1 are placed with their ends resting on the temporary girders 39 and the arch beam sections 15 are placed on the seats 4 of said ceiling slabs, the ends of said arch 125 beam sections abutting, and the reinforcing means projecting from the ceiling beam sections 1 and from the arch slabs 15 into the space between the slabs and between the arch beam sections and over the temporary 130

girders 39 as shown at 3 and 7. When so positioned the ceiling slabs and arch beam sections in conjunction with the temporary girders form the mold for reception of the 5 concrete which is to constitute the permanent girders, suitable reinforcing means, not shown, being inserted within the mold space thus provided for taking the longitudinal 10 tensional strains in usual manner. The concrete or cement is run into said spaces and forms the permanent reinforcing concrete girders and the floor, said floor extending over the arch beam sections 15 as shown at 18, and the concrete girder and floor construction thus formed being tied or interlocked with the arch slabs and ceiling beam sections by the projecting reinforcing means 3 and 7. When the concrete has been run into place as above described and has become 20 hardened, the three-hinge arch beam sections 15 above described become substantially the same as the elastic arch construction, having the same effect as regards the compressive strains brought upon the floor and presenting certain advantages in easy manipulation and of assemblage, and the sections being tied to the girder by the reinforced extensions 3 and 7 forming substantially a cantilever structure supporting the arch on each 25 side. In each of the above described constructions the ceiling slabs are reinforced with wire cloth, expanded metal, steel rods or other suitable form of reinforcing in such manner as to provide tension members of 30 considerable tensile strength to take the tension strain produced by the thrust of the arch members, such a thrust being applied through the seats 4 at the respective ends of the ceiling members.

40. What I claim is:—

1. A ceiling and floor construction comprising preformed ceiling slabs and floor arches, the ceiling slabs having upwardly sloping end faces against which the ends of 45 the floor arches abut, whereby a firm support is afforded, the ends of the ceiling slabs and floor arches of adjacent spans being spaced apart, and concrete beams' molded in the spaces between the slabs and arches and a 50 concrete floor integral with said beams and extending over said arches.

2. A ceiling and floor construction com-

prising preformed ceiling slabs and floor arches, the ceiling slabs having upwardly sloping end faces against which the ends of 55 the floor arches abut, whereby a firm support is afforded and the spring of the arch received by said abutments, the ends of the ceiling slabs and floor arches of adjacent spans being spaced apart, reinforcing members in the ceiling slabs projecting into the spaces, and concrete beams molded in said spaces and around said reinforcing members. 60

3. A ceiling and floor construction comprising ceiling slabs and floor arches which 65 are preformed, there being a separate ceiling slab unit for each floor arch, the ceiling slabs having upwardly sloping end faces against which the ends of the floor arches abut, whereby a firm support is afforded and 70 the spring of the arch received by said abutments, the ends of the ceiling slabs and floor arches of adjacent spans being spaced apart, I-beams located in said spaces and supporting the ceiling slabs by their lower flanges, 75 and concrete floor beams molded into the spaces between the ceiling slabs and arches and around said I-beams.

4. A ceiling and floor construction comprising ceiling slabs and floor arches which 80 are preformed, there being a separate ceiling slab unit for each floor arch, the ceiling slabs having upwardly sloping end faces against which the ends of the floor arches abut whereby a firm support is afforded and the 85 spring of the arch received by said abutments, the ends of the ceiling slabs and floor arches of adjacent spans being spaced apart, I-beams located in said spaces and supporting the ceiling slabs by their lower flanges, 90 said floor arches being spaced at their ends from the I-beams so as to be insertible between the upper flanges of the I-beams and concrete floor beams molded into the spaces between the ceiling slabs and arches and 95 around said I-beams.

In testimony whereof, I have hereunto set my hand at Los Angeles, California, this 18th day of May 1910.

WILLIAM M. THOMAS.
